(57) **CLAIM**

We claim the ornamental design for a reinforcing strut for an overhead door, as shown and described.

DESCRIPTION

FIG. 1 is a perspective view of a first embodiment of a reinforcing strut for an overhead door design broken to show indeterminate length and shown on an overhead door in broken lines for environment according to this invention; FIG. 2 is a perspective view of the reinforcing strut for an overhead door of FIG. 1;

FIG. 3 is a right side view of the reinforcing strut for an overhead door of FIG. 2 with the left side view being a mirror image thereof;

FIG. 4 is a top view of the reinforcing strut for an overhead door of FIG. 2;

FIG. 5 is a bottom view of the reinforcing strut for an overhead door of FIG. 2; and,

FIG. 6 is a front view of the reinforcing strut for an overhead door of FIG. 2 with the back view being a mirror image thereof.
